UNITED STATES PATENT OFFICE.

JAMES A. FENN, OF CHICAGO, ILLINOIS, ASSIGNOR TO PHOENIX-HERMETIC COMPANY, OF CHICAGO, ILLINOIS, A CORPORATION OF NEW YORK.

PROCESS OF STERILIZING HERMETICALLY-SEALED PACKAGES.

Application filed September 27, 1923. Serial No. 665,155.

To all whom it may concern:

Be it known that I, JAMES A. FENN, a citizen of the United States, residing at Chicago, in the county of Cook, State of Illinois, have invented certain new and useful Improvements in Processes of Sterilizing Hermetically-Sealed Packages, of which the following is a description, reference being had to the accompanying drawing and 10 to the figures of reference marked thereon.

The invention relates to new and useful improvements in the art of sterilizing food products, and more particularly to the art of sterilizing food products hermetically 15 sealed in individual packages.

An object of the invention is to provide a process of sterilizing an individual package wherein the contents of the package may be rendered thoroughly sterile in a very 20 short period of time. Another object of the invention is to provide a process of sterilizing individual packages wherein the package may be quickly cooled without breaking the container if the product is packed in a 25 glass container.

The purpose of the invention is to pack food products in containers and a thorough sterilization of the products so that it will keep indefinitely as long as the package is 30 sealed and, at the same time, maintain the color, juices, flavor so far as possible in the product being packed.

In the drawings:

Figure 1 is a view, more or less diagrammatic, of an apparatus for carrying out the process; and

Fig. 2 is a sectional view showing a container.

The food products are packed in individual packages and these packages are hermetically sealed, and then placed in a pressure retort and steam admitted to the retort for the heating of the interior thereof. The steam is preferably passed through a throttle so that the pressure may be regulated to that which is desirable for the sterilizing of the containers in the retort. A jet of water is introduced into the steam pipe leading to the retort, and the steam surrounds said 45 water jet so that, when the steam and water enter the retort, they will be thoroughly intermixed.

When the temperature of the retort reaches approximately 212° F., the retort is put 50 under pressure preferably by means of air.

The purpose of the air pressure is well understood in the art of sterilizing hermetically sealed packages. The air pressure overcomes the internal pressure within the container, due to the heating of the contents thereof, and the expansion of the food products, so that the external air pressure will prevent the cover of the package from being disturbed by this internal pressure, and thus maintaining the packages sealed. Preferably from 10 to 30 pounds of air pressure is used.

The steam which enters the retort is superheated steam and, therefore, can be raised to a temperature of 250° F. The steam pressure will be in the neighborhood of fifteen pounds, and this steam pressure and plus air pressure is sufficient to overcome any internal pressure developing within the container.

The steam is superheated, and the water thoroughly intermixed with this superheated steam, and the water and steam circulate about the retort and contact with the surface of the containers. The water thoroughly intermixed with steam causes the steam to condense and give up its latent heat, which latent heat penetrates to the interior of the containers very quickly and heats the contents thereof to a sterilizing temperature so that all the bacteria and harmful germs will be destroyed.

As one specific example, I have very successfully put up peas by my present method. The container was filled as usual with peas and brine poured over the peas in the container. The cover was loosely placed thereon and the container passed through an exhaust box which heated the contents of the container so that when sealed and allowed to cool to a certain extent, the cover is sealed by the internal vacuum within the container.

The sealed containers were then placed within a retort and the retort closed. Steam intermixed with water was then introduced into the retort, and when the temperature of the retort reached about 212° F., I admitted air under pressure of about 10 pounds. This was for insuring that the cover would be held on the container, notwithstanding the internal pressure within the container due to the heating of the contents and the expansion of the same. Steam intermixed with water was fed to the re-

retort until the retort reached the temperature of about 250°. The retort was kept at this temperature for about fifteen minutes, after which the steam was turned off 5 and water heated by steam to a point so as not to break the glass container was introduced into the retort. The temperature of the water was gradually reduced until the interior of the retort reached a temperature 10 where it was safe to remove the lid.

The peas thus processed were found to be perfectly sterile. The peas also maintained their natural color, as the heating of the contents had been for a relatively short time 15 and had not destroyed the color pigments within the peas. The peas when open had much the flavor of fresh peas. I have also used my process for processing many other kinds of vegetables, including spinach, 20 asparagus and the like with equal beneficial results. The essential features of the process consists in the quick sterilizing of the food products so that while the bacteria and objectionable germs are destroyed, the food 25 product is not overcooked or discolored but maintains much of its natural color and flavor.

In the drawings, the retort is indicated at 1, and said retort is closed by a lid 2. The air is introduced into the retort by a pipe 3 controlled by a valve 4. The pipe 5 leads from the main steam line and delivers steam to a pipe 6 connected to the retort and controlled by a valve 7. The steam pressure of 35 the main line is controlled by a hand valve 8. A water pipe 9 is connected to a coupling 10 on the end of the pipe 6, and a nozzle 11 connected with this water pipe 9 extends into the coupling beyond the point where the steam enters the coupling so that the steam surrounds the nozzle. The water is controlled by a valve 12. The water is introduced into the pipe 6 at a slightly greater 40 pressure than the water, and becomes thoroughly intermixed with the steam so that, when the steam reaches the retort and surrounds the individual containers, the steam is thoroughly intermixed with water. A suitable water gauge 13 is provided, and

50 a suitable steam gauge 14. A thermometer 15 is used for determining the temperature of the intermixed steam and water passing to the retort. A drain pipe 16 leads from the retort. The water pipe 9 is connected to the drain by a pipe 17. 55

For the purpose of cooling the retort, I have provided a mixing chamber 18 which is connected by means of the pipe 19 to the main water line and by means of the pipe 20 to the main steam line. The steam heats 60 the water in this mixing chamber, and the water is led through a pipe 21 to the retort. By this means, the water can be heated to the proper temperature so as not to break 65 the glass containers and gradually can cool down.

In Fig. 2, I have shown a glass container at G and a lid or cover g therefor, which is suitable to be used in connection with my process. It will be understood that 70 instead of using glass, metal may be used. The apparatus set forth above is shown, described and claimed in my copending application Serial No. 665,154, filed of even date herewith. 75

It is obvious that other forms of apparatus may be used for carrying out the process, and that the details stated may be widely varied without departing from the spirit of the invention as set forth in the appended 80 claim.

What I claim is:—

The process of sterilizing hermetically sealed packages comprising placing a sealed package in a closed retort, surrounding the 85 sealed package in said retort with super-heated steam, and intermixing water with the super-heated steam as it enters the retort so that the container will be surrounded with super-heated steam thoroughly intermixed with water which will aid in the condensing of the steam on the wall of the container, and thereby transferring the latent heat of the steam to the contents of the container for sterilizing the same. 90 95

In testimony whereof, I affix my signature.

JAMES A. FENN.
